UNITED STATES PATENT OFFICE.

HOWARD E. SAVAGE, OF BOSTON, MASSACHUSETTS.

VEHICLE.

Specification of Letters Patent. Patented July 29, 1919.

1,311,420.

Application filed March 17, 1919. Serial No. 283,005.

To all whom it may concern:

Be it known that I, HOWARD E. SAVAGE, a citizen of the United States, residing at Boston, in the county of Suffolk and State of Massachusetts, have invented certain new and useful Improvements in Vehicles; and I do hereby declare the following to be a full, clear, and exact description of the same, reference being had to the accompanying drawings, forming a part of this specification, and to reference characters marked thereon.

My invention relates to improvements in vehicles, and has for its object to provide more particularly, a toy vehicle of the velocipede type, the body or seat of which may be easily adjusted, in a horizontal position, to any one of several possible heights above the running surface, to accommodate children of different sizes, whereby the child's feet 20 may be suitably engaged with the running surface, and by a paddling or walking motion propel the vehicle in any desired direction.

Another object of my invention is to provide as large a forward, or steering wheel, as possible, and materially larger than the rear wheels, in order to give an easier rolling tendency, upon a running surface, than can be obtained by the use of relatively small 30 wheels, all of the same diameter.

A further object of my invention is to provide a sliding plate at the front or head end of the body to carry the steering post, whereby the same may be adjusted to different positions to accommodate children 35 having arms of different lengths, and an improved inclined rear body support which will give an increasing wheel base to the vehicle as the body is adjusted to its higher 40 positions.

To these and other ends, the invention consists in certain improvements and combinations of parts, all of which are hereinafter more completely described, the novel feature 45 being pointed out in the claims at the end of the specifications.

In order that those skilled in the art to which this invention appertains, may understand how to make and use the same, I will 50 describe its construction and combination of elements.

In the drawings:

Figure "1" is a top plan view showing the

body of the vehicle adjusted at its minimum height.

Fig. "2" is a top plan view of the front or head end of the body at the position indicated upon Fig. "3" by the line and arrows "2-2," showing also a cross-section of the steering post.

Fig. "3" is a side elevation showing the body adjusted to its minimum height, and with the steering post set at its nearest point to the rear end of the body.

Fig. "4" is a side elevation showing the body adjusted to its maximum height, and with the steering post set at its farthest position from the rear end of the body, a portion of the forward parts of the vehicle being shown in section.

Fig. "5" is a front elevation showing the body adjusted to its minimum height.

Fig. "6" is a front elevation showing the body adjusted to its maximum height.

Fig. "7" is a rear elevation showing the body adjusted to its maximum height.

Fig. "8" is a rear elevation showing the body adjusted to its minimum height.

Similar reference characters throughout the several views indicate the same parts.

On the drawings I have shown, most clearly in Fig. "1," a seat board, or body member "10," a portion of which is comparatively narrow "11," to permit a child to easily straddle the vehicle when operating the same. A wider part "12" at the rear forms a seat, and an enlarged portion "13" at the opposite end forms the head end.

In the head end is an enlarged longitudinal aperture "14," most clearly shown in Fig. "2," with semi-circular ends, adapted to receive the steering post "15," and to allow it to move forward and backward therein. Two parallel, narrow, longitudinal slots "16" one on each side of the aperture "14," act as guides for the sliding head plate "17," most clearly shown in Fig. "4," by means of the countersunk bolts "18" with washer and nut "19" on the underside of the body "13". The bolts "18" may be tightly fastened at any point in the slots, holding the steering post securely at that position. The sliding head plate "17" is made tapering with the thick end at the front. Through this plate "17" passes a circular hole adapted to permit a reduced part of the steering

post "25" to revolve therein. On the underside of plate "17" is a counter-bored portion, adapted to act as a bearing surface for supporting the front end of the body on a circular shoulder formed on the steering post "15", also adapted to permit the steering post to revolve freely therein. The steering head is here shown as an imitation horse's head "27" with handle bars "28" and bolted 10 to the steering post by means of the bolt washers and nut "26". The steering post "15" has a deep longitudinal slot or bifurcation extending from the bottom end to a point in line with the underside of the head 15 end, forming a steering fork. This fork has the scarfed-off surface "20" through which pass a series of equally spaced round holes "24" directly opposite each other in the two prongs, and adapted to receive the bolt or pin "22", with washer, and cotter pin "23". The bolt 22 acts as an axle for the large, front steering wheel "21", said steering wheel "21" being a trifle larger in diameter than the length of the bifurcation in the 25 steering post "15" so that the bottom end of the steering post "15" will always clear the running surface. The axle "22" may be inserted through any of the holes "24" to adjust the wheel to any position in relation 30 to the body, which will correspond with a certain adjustment of the rear wheel carrier "39" to give a horizontal position to the body, at the desired height above the running surface, or the body, if so desired, may 35 be adjusted to a sloping position.

The rear body support or bolster "29" is fastened to the body "12," by means of screws "30," and rigidly braced by means of the brace "31," and screws "32," "33" and 40 "34," "34" having a counter-sunk head to allow the rear wheel carrier "39" to lie flat against the bolster "29." The bolster "29" is placed in a backward inclined position to aid in obtaining a greater wheel base as the 45 body of the vehicle is raised from its lowest to its higher positions. This purpose is also partly accomplished by the forward sloping steering part "15," made possible by the tapering head plate "17," with its inclined 50 supporting surface, on the bottom side, as may be clearly seen in Figs. "3" and "4."

The rear wheel carrier "39" carries two small wheels "40" with large screws "41" acting as axles. The carrier "40" is made 55 wide, in order to permit the action of a child's feet inside of the wheels, and to give greater stability and less tipping tendency to the vehicle. The bolster "29" has through it a series of equally spaced, round holes, 60 "36" in two parallel vertical rows. The rear wheel carrier "39" has fastened to it, and projecting from it, two bolts "35" adapted to aline with the holes "36," to enter any horizontal pair of these holes and by means

of the wing nuts "38" with washers "37" 65 beneath, to be securely bolted to the bolster "29." The holes "36" in the bolster "29" are so located that they will correspond with the holes "24" in the steering fork "15" to give a horizontal position to the body in the 70 several different levels possible by adjustment of both ends of the vehicle.

It will thus be clearly observed that the vehicle here described, is of simple, rigid construction, easily adjusted to accommodate 75 children of different ages or sizes, having a considerable range of adjustability, great stability, and an easy running tendency.

While I have indicated the preferred form 80 of my child's vehicle it is very evident that minor changes in its design may, for manufacturing or commercial reason, be made, without departing from the spirit of my invention.

I claim:

1. The combination in a child's vehicle of a body having a sliding head plate in which a forwardly inclined steering post is rotatably carried, said head plate being tapering with the thick end at the front, in order to give the desired forward inclination to the steering post, and having a circular recess or counterbore concentric with the steering post on its under side adapted to 95 act as a bearing or supporting surface to take the upward thrust of a shoulder on the steering post; said head plate being adjustably attached to the body and adapted to slide forward or back, carrying the steering 100 post with it, with bolts and nuts for clamping the same to the body, said bolts working in two parallel, longitudinal slots, one on each side of a steering post aperture in the body.

2. The combination in a child's vehicle of a steering post having a long bifurcation, adapted to receive a wheel of practically the same diameter as the length of said bifurcation, a series of equally spaced, transverse, 110 round holes, passing through both prongs of the steering post, formed by the said bifurcation, adapted to receive an axle, upon which a wheel may revolve at any one of the several positions offered by said series 115 of holes, in said prongs, and a rear body bolster having a series of equally spaced round holes, in two vertical rows, passing through it, adapted to receive two bolts projecting from a rear wheel carrier, at any one 120 of the several positions offered by said series of holes in said bolster.

3. The combination in a child's vehicle of a body having a forward inclined steering post, and an inclined bolster permanently 125 attached to the body, at a constant backward angle to the same, and containing a series of round, equally spaced holes, in two verti-

cal parallel rows passing through the same from front to back, a removable rear wheel carrier, with wheels rotatably attached thereto, and having two bolts with threaded ends, attached to the same, adapted to register with the series of holes in the bolster, whereby the said wheel carrier may be securely clamped in a horizontal position to

the bolster, at any one of the several positions offered by said series of holes, the bolts 10 being provided with wing nuts and washers as a means of fastening.

In testimony whereof, I have hereunto affixed my signature.

HOWARD E. SAVAGE.
